Rudolph Dannecker, Beacon, N. Y.

Application October 16, 1937, Serial No. 72,234

To all whom it may concern:

Be it known that I, Rudolph Dannecker, a citizen of the United States, residing in Beacon, county of Dutchess, and State of New York, have invented a new, original, and ornamental Design for a Textile Fabric or Similar Article, of which the following is a specification, reference being had to the accompanying drawing, forming part thereof.

The figure is a plan view of a textile fabric showing my new design.

The characteristic feature consists of a series of floral like elements raised from a crinkled background giving the design as a whole a crepe appearance.

I claim:

The ornamental design for a textile fabric or similar article as shown and described.

RUDOLPH DANNECKER.
